CLAIM

The ornamental design for a timepiece, as shown and described.

DESCRIPTION

FIG. 1 is a front elevational view of a timepiece showing my new design;

FIG. 2 is a rear elevational view;

FIG. 3 is a left side elevational view;

FIG. 4 is a right side elevational view;

FIG. 5 is a top plan view; and,

FIG. 6 is a bottom plan view thereof.

The structure depicted by means of broken lines has been shown for illustrative purposes only and forms no part of the claimed design.
